CLAIM

The ornamental design for an electrical connector, as shown and described.

DESCRIPTION

FIG. 1 is a perspective view of an electrical connector showing my new design;

FIG. 2 is a front view thereof, the rear view being a mirror image;

FIG. 3 is a top view thereof, the bottom view being a mirror image;

FIG. 4 is a left end view thereof;

FIG. 5 is a right end view thereof;

FIG. 6 is perspective view thereof, showing an alternate usage environment;

FIG. 7 is a front view thereof, the rear view being a mirror image;

FIG. 8 is a top view thereof, the bottom view being a mirror image;

FIG. 9 is a left end view thereof; and,

FIG. 10 is a right end view thereof.

The dotted broken lines are environmental and form no part of the claimed design. The dash-dot-dot lines indicate boundaries of the claimed design, and form no part thereof.
